HYDROCARBON OIL CONVERSION

Joseph G. Alther, Chicago, Ill., assignor to Universal Oil Products Company, Chicago, Ill., a corporation of Delaware

Application January 15, 1937, Serial No. 120,681

14 Claims. (Cl. 196—49)

This application is a continuation-in-part of my co-pending application Serial No. 516,021, filed February 16, 1931, which has now become abandoned.

5 The invention relates to an improved process for the cracking of hydrocarbon oils to produce high yields of good quality gasoline and minor yields of high-boiling residual liquids accompanied by the reduction of all or a portion of the 10 latter to substantially dry coke, said coking being accomplished, in the present invention, by quickly heating said residual oil, following its separation from lower boiling vaporous products and in commingled state with a selected substantially lower 15 boiling hydrocarbon oil derived from within the system, to a high cracking temperature under non-coking conditions and introducing the resultant highly heated mixture into a coking zone wherein their high-boiling components are reduced to coke by the contained heat of the mixture.

20 My aforementioned co-pending application discloses a combination cracking and coking system wherein heavy residual oils resulting from the 25 reduced pressure or "flash" distillation of liquid conversion products, resulting from the cracking of lower boiling hydrocarbon oils, are reduced to coke in one of several alternatively non-equivalent manners, each of which involves further 30 heating of the flashed residual liquid, either by passing the same through a heating coil or by commingling the same with a heat carrying medium comprising relatively light intermediate liquid products of the process, to a sufficiently high 35 temperature to induce to its further vaporization and reduction of the resultant non-vaporous components to coke in a coking zone separate from the zone of said flash distillation.

40 This continuation-in-part is directed specifically to that embodiment of the parent application wherein all or a regulated portion of the flashed residual liquid from the vaporizing or flash distilling zone of the cracking system is commingled with a selected relatively low-boiling 45 oil derived from within the system, the commingled materials passed through a heating coil separate from that of the primary cracking zone and therein subjected to a relatively high cracking temperature, under conditions which pre- 50 clude the formation and deposition of any substantial quantity of coke in the heating coil, and the resultant highly heated commingled materials passed into a coking zone wherein their contained heat effects vaporization of all but 55 their undesirable high-boiling components and

also effects reduction of the latter to coke, the coking zone being separate and apart from other portions of the system to the extent that only heated products from said separate heating coil are supplied thereto.

5 The relatively low-boiling oil commingled with the high-boiling residual liquids subjected to said coking comprises selected relatively low-boiling fractions of the reflux condensate resulting from fractionation of the vaporous conversion products 10 of the first mentioned cracking step and, when desired, may also include selected low-boiling fractions of the charging stock and/or selected low-boiling fractions of the reflux condensate resulting from fractionation of the vaporous products 15 of the coking step, the components and the nature of this material being selected to suit requirements and being in any case of such nature that it will be substantially vaporized under the conditions and treatment to which it is subjected in said heating coil and coking zone and preferably such that it is further cracked under these 20 conditions to produce additional yields of desirable low-boiling products within the range of gasoline.

Components of the reflux condensate which 25 are of a higher boiling nature than the selected fractions subjected to treatment with the high-boiling residual liquids are preferably supplied to the first mentioned cracking step of the system for further cracking, and hydrocarbon oil charging stock of the process, depending upon its characteristics, may be either cracked in commingled state with said high-boiling components of the reflux condensate, or it may be separated, when desired, into selected relatively low and high-boiling 30 fractions, such separation being preferably effected by subjecting the charging stock to fractionation together with said vaporous conversion products, in which latter case, the high-boiling 35 fractions of the charging stock are supplied to the initial cracking step for conversion together with the high-boiling components of the reflux condensate, while the selected low-boiling fractions of the charging stock are supplied to said 40 separate heating coil together with said high-boiling residual liquids and said selected low-boiling fractions of the reflux condensate.

I am fully aware that the teachings of this invention appear contrary to the previously established concepts of the best methods of cracking and/or coking heavy oils. The best previous methods of cracking have all tended toward the selective segregation of relatively low-boiling and high-boiling oils accompanied by the cracking of

5

35

40

45

50

55

each selected fraction under independently controlled conditions of temperature, pressure and time and have distinctly voided mixing of relatively low-boiling and relative high-boiling oils in the cracking coil. Previous attempts at cracking oils of widely different boiling range in commingled state have resulted in the excessive formation and deposition of coke in the heating coil with its attendant hazards and severe penalties with respect to the useful life of the equipment and the duration of the operating cycle of the process. However, I now believe that these previous concepts of the advantages of selective cracking are only partially correct and while they are almost universally applicable as applied to the usual run of cracking stocks, they do not necessarily apply to the further cracking and coking of heavy residual oils such as those resulting from the flash distillation of the liquid conversion products of a modern cracking operation. The failure of previous attempts have been explained by the theory that the presence of low-boiling oils in the same cracking coil with relatively high-boiling oils, results in excessive vaporization in this zone, leaving a thin film of exceptionally high-boiling oil on the inner surface of the tubular heating coil through which the mixture is passed, which film tends to adhere to the surface of the tube and is readily reduced thereon to coke under the high temperature conditions normally employed in the cracking furnace. However, by selecting as the only components of the mixture, an oil of exceptionally high-boiling characteristics and an oil of much lower boiling characteristics, by blending the same in such proportions that the high-boiling oil comprises a substantial proportion of the mixture and by quickly heating the mixture to the desired relatively high temperature, I have found it possible to heat the mixture to a sufficiently high temperature to induce subsequent coking of its non-vaporous components and appreciable cracking of its vaporous components and still avoid coking difficulties in the heating coil and communicating lines, while producing a good quality coke and substantial additional yields of desirable low-boiling products, such as good antiknock gasoline.

While it is not the purpose of this application to offer a theoretical explanation for the success of this operation, I believe that it can be accounted for, at least in part, by the fact that I employ a sufficient quantity of sufficiently heavy oil in the mixture supplied to the heating coil to maintain a substantial body of liquid on the surface of the tubular elements of the heating coil, which heavy liquid acts as a wash for the walls of the tubes, keeping the same relatively clean and free from carbon deposits and functioning in much the same manner as the heavy liquid supplied to the walls of a high pressure reaction chamber, the value of the latter expedient being well recognized in the art. The relatively high oil velocity which I preferably employ in this coil increases the efficiency of the heavy liquid as a washing or scrubbing medium and these factors, in combination with the relatively short time and high pressure preferably employed in a heating coil, are believed to account to a large extent for the success of the operation. I also believe that the wide difference in boiling characteristics between the light and heavy components of the mixture is an important factor, the result being a truly mixed-phase condition with a substantial quantity of the mixture maintained in liquid state. I further believe that all of the factors men-

tioned are essential and cooperate to produce the desired result. It also seems probable that there is some interaction of a chemical nature between the light and heavy components of the mixture, during and/or subsequent to their passage through the heating coil, which accounts, at least in part, for the improved yields of gasoline obtained, and I have found that the antiknock quality of the gasoline produced is improved when fairly high superatmospheric pressure is employed in the coking zone. This is, no doubt, due to the additional conversion time afforded the mixture and, more particularly, its low-boiling vaporous components, in the coking zone. However, when high pressure is employed in the coking zone, the volatility of the coke produced is normally somewhat higher and it is therefore a matter of choice as to whether the coking zone is operated at relatively low pressure, depending in part upon the nature of the charging stock and in part upon the other operating conditions employed, as well as the desired quality of the final products.

The accompanying diagrammatic drawing illustrates one specific form of apparatus employing the feature of the invention and in which the process of the invention may be successfully conducted.

Referring to the drawing, the charging stock which may be an oil of any desired characteristics but is preferably of relatively high-boiling nature or relatively wide boiling range, such as for example, crude petroleum, topped crude and the like, is supplied through line 1 and valve 2 to pump 3 wherefrom it is fed from line 4 and may pass all or in part through line 6 and valve 7 into fractionator 8, to commingle therein with the vaporous conversion products in this zone and be subjected to fractionation therewith, or the charging stock may be passed all or in part through valve 9 in line 4 into a suitable closed coil or other heat exchange apparatus 10 disposed within fractionator 8, wherein it is heated by indirect heat exchange with the relatively hot vaporous products undergoing fractionation and wherefrom it is directed through line 11, valve 12, line 13 and valve 18 to conversion in heating coil 19. It is, of course, also within the scope of the invention to preheat the charging stock to any desired degree in any other well known manner not illustrated prior to its introduction into heating coil 19, or it may be supplied thereto, all or in part, without being preheated.

High-boiling fractions of the reflux condensate formed in fractionator 8 are also supplied to heating coil 19, as will be later described and the mixture passing through this zone is heated to desired cracking temperature preferably at a substantial superatmospheric pressure by means of heat supplied from furnace 20. The heated products are discharged from coil 19 through line 21 and valve 22 into reaction chamber 23.

Reaction chamber 23 is also preferably maintained at a substantial superatmospheric pressure and although not indicated in the drawing, it is preferably insulated to conserve heat, so that the hot conversion products supplied to this zone are subjected to appreciable continued conversion therein.

In the particular case here illustrated, both vaporous and liquid conversion products are discharged from the lower portion chamber 23 through line 24 and valve 25 into vaporizing and separating chamber 26 and, although this is the preferred method of operation, it is also within

the scope of the invention to separate the vaporous and liquid products in chamber 23, in which case, the liquid products, either alone or together with a minor portion of the vapors, are supplied 5 through line 24 and valve 25 to chamber 26 while all or the remaining portion of the vapors are withdrawn from any other suitable point in the reaction chamber and directed, by well known means not illustrated, either to fractionator 8 or 10 to chamber 26 or in part to both. When all or a portion of the vaporous products separately withdrawn from chamber 23 are supplied to chamber 26, they may be either commingled with line 24 with the liquid products passing to chamber 26, 15 or they may be separately supplied to this zone at any desired point therein.

Chamber 26 is preferably operated at a substantially reduced pressure relative to that employed in the reaction chamber by means of 20 which appreciable further vaporization of the liquid products supplied to this zone is accomplished, leaving a relatively heavy liquid residue in this zone which is withdrawn from the lower portion thereof through line 39 and subjected all 25 or in part to further treatment, as will be later described.

The vaporous products supplied to chamber 26 from the reaction chamber as well as the vapors evolved from the liquid products in this zone, are directed therefrom through line 27 and valve 28 30 to fractionation in fractionator 8, commingling therein with the charging stock or any portion thereof which is supplied to the fractionator as previously described. The components of the materials supplied to fractionator 8 boiling above the range of the desired final light distillate product of the process, which is normally gasoline, are separated by fractionation in this zone into selected relatively low-boiling and high-boiling 40 fractions which, for the sake of convenience, will hereinafter be termed low-boiling and high-boiling reflux condensates, although either or each of the fractions may include components of the charging stock when all or a portion of the latter is supplied to the fractionator.

Fractionated vapors of the desired end-boiling point are withdrawn together with normally gaseous products from the upper portion of fractionator 8 and directed through line 29 and valve 30 50 to condensation and cooling in condenser 31. The resulting distillate and uncondensed gases pass through line 32 and valve 33 to collection and separation in receiver 34. The uncondensed gases may be released from the receiver through line 35 and valve 36. The distillate products may be withdrawn through line 37 and valve 38 to storage or to any desired further treatment.

When desired, regulated quantities of the distillate collected in receiver 34 may be recirculated, 60 by well known means not illustrated, to the upper portion of fractionator 8 to serve as a cooling and refluxing medium in this zone.

The selected high-boiling components of the reflux condensate formed in fractionator 8 are directed from the lower portion of this zone through line 14 and valve 15 to pump 16 by means of which they are returned through line 13, valve 17 and valve 18 to further cracking in heating coil 19.

70 The heavy residual liquids remaining unvaporized in chamber 26 are withdrawn, as previously mentioned, from the lower portion of this zone through line 39 and a regulated portion of this material may, when desired, be removed from the system as a final product thereof through line 41

and valve 42 to cooling and storage, or elsewhere, as desired. However, at least a portion of the heavy liquid residue is directed through valve 40 in line 39 to pump 43 by means of which it is directed through line 44 and valve 45 to heating coil 46.

The low-boiling fractions of the reflux condensate selected for blending and treatment with the heavy residual liquid, may be withdrawn from one or a plurality of suitable intermediate points in the fractionator, lines 47 and valves 48 being provided for this purpose and directed through line 49 to pump 50 by means of which this material is directed through line 51 and valve 52 into line 44 to commingle therein with the residual liquid from chamber 26, passing therewith to treatment in heating coil 46. These lower boiling fractions of the reflux condensate may comprise such materials as light gas oil, kerosene or kerosene distillate, pressure distillate bottoms, naphtha, high-boiling gasoline fractions of unsatisfactory antiknock value, or any desired mixture of such materials.

The commingled stream of low-boiling and high-boiling oils is heated in coil 46 preferably to 23 a relatively high cracking temperature, by means of heat supplied from furnace 53, the heating coil preferably being of such design, several forms of which are now well known, as to permit the use of high velocity in the heating coil with rates of 30 heating adequate to bring the oil quickly to the desired temperature without allowing it to remain in the heating coil for a sufficient length of time to permit any substantial formation or deposition of coke therein. A sufficiently high pressure to 35 keep at least a substantial portion of the heavy liquids supplied to heating coil 46 in liquid-phase during their passage through this zone, is also preferably employed and this high pressure also favors conversion of the low-boiling components of the 40 mixture into additional yields of good quality gasoline without excessive coke and gas formation.

The highly heated mixture is discharged from heating coil 46 through line 54 and is directed through line 55 and valve 56 into coking chamber 45 57 and/or through line 55' and valve 56' into coking chamber 57', wherein the high-boiling non-vaporous components of the mixture are reduced by its containing heat to substantially dry coke.

Coking chambers 57 and 57' are similar zones which may be operated at substantially the same or lower pressure than that employed at the outlet of heating coil 46. A single coking chamber or any desired number of a plurality of such 55 zones may, of course, be employed and when two or more chambers are utilized they preferably are alternately operated, cleaned and prepared for further operation, in order that the operating cycle will not be limited by the capacity of the 60 coking zone. The coke produced is allowed to accumulate in chambers 57 and 57' and may be removed therefrom in any well known manner, not illustrated, after their operation has been completed and preferably after they have been 65 isolated from the rest of the system. Chambers 57 and 57' are provided with suitable drain lines 58 and 58', respectively controlled by the respective valves 59 and 59' and this facility may also serve as a means of introducing steam, water or 70 any other suitable cooling medium into the chambers after their operation has been completed and preferably after they have been isolated from the rest of the system, in order to hasten cooling and facilitate removal of the coke. Vaporous

products are withdrawn from the upper portion of chambers 57 and 57' through lines 60 and 60' respectively controlled by the respective valves 61 and 61' and are thence directed through line 5 62 and either through valves 63 in this line and through line 27 into fractionator 8, or preferably through line 64 and valve 65 into chamber 26.

The vaporous products of the coking operation are preferably directed to chamber 26 for the 10 reason that they will normally contain entrained or dissolved high-boiling materials unsuitable as components of the reflux condensate supplied to heating coil 19. By supplying the vapors to chamber 26 at least a major portion of any undesirable 15 high-boiling materials in the vapors may be removed therefrom and collected with the residual liquid in this zone, to be returned therewith to further treatment in heating coil 46. Suitable fractionating means of any well known 20 form, not illustrated, such as baffles, bubble trays, perforating pans, liquid sprays or the like, may be employed, when desired, in the upper portion of chamber 26 to assist in removing any undesirable 25 heavy components from the vaporous products supplied from this zone to fractionator 8, thereby keeping the reflux condensate relatively clean and substantially free of high coke-forming components.

In order to better regulate the proportions of 30 light and heavy oils in the mixture supplied to heating coil 46, provision is made, in the case here illustrated, for supplying only a regulated portion of the low-boiling reflux to heating coil 46 and removing the remainder, all or in part, 35 from the system through line 67 and valve 68 to cooling and storage, or elsewhere as desired, or directing the same, all or in part to further cracking in heating coil 19 by means of line 69, valve 70, line 13 and valve 18.

40 The preferred range of operating conditions which may be employed to successfully conduct the process, in an apparatus such as illustrated and above described, may be approximately as follows: The heating coil to which the high-boiling reflux condensate and/or high-boiling 45 fractions of the charging stock are supplied for conversion, may employ an outlet temperature of from 650° to 950° F. or thereabouts, preferably with a superatmospheric pressure, measured 50 at the outlet from the heating coil, of from 100 to 500 pounds or more per square inch. A superatmospheric pressure of substantially the same order is preferably employed in the succeeding 55 reaction chamber, although this zone may be operated at a lower superatmospheric pressure than that employed in the heating coil, the vaporizing and separating chamber, as previously mentioned, preferably employing a substantially reduced pressure relative to that utilized in the 60 reaction chamber which may range for example from 150 pounds or thereabouts per square inch down to substantially superatmospheric pressure, the preferred range being a superatmospheric 65 pressure of from 25 to 80 pounds or thereabouts per square inch.

The heating coil of the coking stage of the system preferably employs an outlet temperature of the order of from 900 to 1000° F. and preferably a superatmospheric pressure of from 100 to 70 800 pounds per square inch, or thereabouts, is employed in this zone although lower pressure may be employed when desirable. The coking zone may employ substantially the same pressure as that maintained at the outlet from the 75 heating coil of the coking stage of the system,

or any desired lower pressure down to substantially atmospheric. The fractionating condition and collecting portions of the system may be operated at substantially the same or somewhat lower pressure than that employed in the vaporizing chamber. 5

As an example of one specific operation of the process, as it may be conducted in an apparatus such as illustrated and described, the charging stock, which is a fuel oil of about 18° A. P. I. gravity, after being preheated by indirect heat exchange with the vaporous products in the fractionator is supplied to the heating coil of the cracking system together with high boiling fractions of the reflux condensate; wherein the commingled oils are heated to an outlet conversion temperature of approximately 940° F. at a superatmospheric pressure of about 350 pounds per square inch, substantially the same pressure is maintained in the reaction chamber and both 20 vaporous and liquid conversion products are supplied from the reaction chamber to the vaporizing and separating chamber which is maintained at a superatmospheric pressure of approximately 50 pounds per square inch. This pressure is substantially 25 equalized in the fractionating conditions and collecting equipment. In this operation the total liquid residue from the vaporizing and separating chamber is commingled with about an equal amount, by volume, of low-boiling 30 reflux condensate, which latter has a boiling range of approximately 390 to 560° F., and the resultant mixture is quickly heated in the heating coil of the coking stage of the system to an outlet temperature of approximately 970° F. at a superatmospheric pressure of about 400 pounds per square inch. Relatively short time high velocity 35 is employed in this heating coil and the heated materials are quickly transferred therefrom to alternately operating coking chambers maintained at superatmospheric pressure of approximately 40 250 pounds per square inch. Vaporous products from the coking chambers are supplied to the vaporizing and separating chamber. This operation will produce, per barrel of charging 45 stock, approximately 65% of 400° F. yield point gasoline having an octane number of approximately 70 by the motor method and approximately 85 pounds of good quality petroleum coke, the remainder being chargeable principally to 50 normally gaseous products.

I claim as my invention:

1. In a process for the conversion of hydrocarbon oils wherein an oil, comprising essentially 55 charging stock for the process and selected high-boiling fractions of the reflux condensate formed in the process, is cracked at cracking temperature and substantial superatmospheric pressure, thereby forming vaporous and liquid conversion products, the latter reduced to high-boiling 60 residual oil by flash distillation, the vaporous products, including those resulting from said flash distillation, subjected to fractionation for the formation of reflux condensate, fractionated vapors of the desired end-boiling point condensed 65 and resulting distillate recovered, the improvement which comprises commingling at least a substantial portion of said high-boiling residual oil with a regulated portion of said reflux condensate, passing the resultant mixture through 70 a heating coil and quickly heating the same therein under independently controlled, non-coking conditions sufficiently to effect subsequent coking of its high-boiling components and appreciable cracking of its low-boiling components, in- 75

roducing the heated material from the last mentioned heating step into an enlarged coking zone wherein vaporous and non-vaporous components of the heated mixture are separated and the latter reduced to coke without additional heating, and fractionating vaporous products of the coking step in admixture with the first-mentioned vaporous products.

2. In a process for the conversion of hydrocarbon oils wherein an oil is cracked at cracking temperature and substantially superatmospheric pressure, thereby forming vaporous and liquid conversion products, the latter reduced to high-boiling residual oil by flash distillation, the vaporous products, including those resulting from said flash distillation, subjected to fractionation for the formation of reflux condensate, fractionated vapors of the desired end-boiling point condensed and resulting distillate recovered, the improvement which comprises supplying at least a portion of the hydrocarbon oil charging stock for the process to said fractionating step wherein it is subjected to fractionation in commingled state with said vaporous conversion products, commingling at least a substantial portion of said high-boiling residual oil with a regulated portion of said reflux condensate, passing the resultant mixture through a heating coil and quickly heating the same therein under independently controlled, non-coking conditions sufficiently to effect subsequent coking of its high-boiling components and appreciable cracking of its low-boiling components, introducing the heated material from the last mentioned heating step into an enlarged coking zone wherein vaporous and non-vaporous components of the heated mixture are separated and the latter reduced to coke without additional heating, and fractionating vaporous products of the coking step in admixture with the first-mentioned vaporous products.

3. A process such as defined in claim 2 wherein the portions of said charging stock which remain unvaporized in the fractionating step are supplied, together with high-boiling fractions of the reflux condensate, to the first mentioned cracking step.

4. A process such as defined in claim 2 wherein the portions of said charging stock which remain unvaporized in the fractionating step are supplied, together with high-boiling fractions of the reflux condensate, to the first mentioned cracking step and wherein said portion of the reflux condensate commingled with said high-boiling residual oil includes selected fractions of the charging stock.

5. In a process for the conversion of hydrocarbon oils wherein an oil is cracked at cracking temperature and substantial superatmospheric pressure, thereby forming vaporous and liquid conversion products, the latter reduced to high-boiling residual liquid by flash distillation, the vaporous products, including those resulting from said flash distillation, subjected to fractionation for the formation of reflux condensate, fractionated vapors of the desired end-boiling point condensed and the resulting distillate recovered, the improvement which comprises separating selected low-boiling fractions from the reflux condensate commingling at least a substantial portion of said high-boiling residual liquid with regulated quantities of selected low-boiling fractions of the reflux condensate, supplying the resultant mixture to a heating coil and quickly heating the same therein, under independently controlled, non-coking conditions, to a temperature sufficient to

effect subsequent coking of its high-boiling components and appreciable cracking of its low-boiling components, supplying the heated materials from said heating coil to an enlarged coking zone, wherein separation of their vaporous and non-vaporous components is accomplished and the latter reduced to coke without additional heating, and fractionating vaporous products of the coking stage in admixture with the first-mentioned vaporous products.

6. A process such as defined in claim 5 wherein high-boiling fractions of the reflux condensate are returned to the first mentioned cracking step.

7. A process such as defined in claim 5 wherein that portion of the reflux condensate which is not commingled with said high-boiling residual oil is returned for further cracking to the first mentioned cracking step.

8. A process such as defined in claim 5 wherein at least a portion of the hydrocarbon oil charging stock for the process is supplied to said fractionating step and subjected to fractionation therein, in commingled state with said vaporous products, and wherein at least a portion of said charging stock is cracked in the first mentioned cracking step.

9. A process such as defined in claim 5 wherein high-boiling fractions of the reflux condensate and high-boiling fractions of the charging stock are supplied to the first mentioned cracking step and wherein said selected low-boiling fractions of the reflux condensate which are commingled with said high-boiling residual oil include selected low-boiling fractions of the charging stock.

10. In a process for the conversion of hydrocarbon oils which comprises heating an oil to cracking temperature at substantial superatmospheric pressure in a heating coil, supplying the heated products to an enlarged reaction chamber, also maintained at substantial superatmospheric pressure, wherein appreciable further cracking thereof is accomplished, supplying both vaporous and liquid conversion products from the reaction chamber to a reduced pressure vaporizing and separating chamber, wherein appreciable further vaporization of said liquid products is accomplished and wherein vaporous products are separated from the resultant residual liquid, fractionating the vaporous products from said vaporizing and separating chamber for the formation of reflux condensate, separating said reflux condensate into selected relatively low-boiling and high-boiling fractions, returning said high-boiling fractions of the reflux condensate to the heating coil for further cracking, subjecting fractionated vapors of the desired end-boiling point to condensation, recovering the resulting distillate, commingling at least a substantial portion of said residual liquid with regulated quantities of said selected low-boiling fractions of the reflux condensate, passing the resultant mixture through a separate heating coil and heating the same therein at substantial superatmospheric pressure to a sufficiently high temperature to induce subsequent coking of its high-boiling components and appreciable cracking of its low-boiling components, regulating the conditions of treatment in said separate heating coil to maintain said mixture in a mixed-phase condition therein, discharging the resultant highly heated mixture from said separate heating coil and introducing the same into an enlarged coking zone, also maintained at a sufficiently high superatmospheric pressure to effect appreciable cracking of the vaporous components of the mixture at their

attained temperature in this zone and wherein the non-vaporous high-boiling components of the mixture are reduced to coke, removing undesirable high-coke forming components from the 5 vaporous products of the coking step, returning the same to the coking step for further treatment, subjecting the remaining relatively clean vaporous products of the coking step to fractionation for the formation of reflux condensate, 10 returning the latter to further cracking within the system, condensing fractionated vapors of the desired end-boiling point from the last mentioned fractionating step, and recovering the resultant distillate.

15 11. In a process for the conversion of hydrocarbon oils which comprises heating an oil to cracking temperature at substantial superatmospheric pressure in the heating coil, supplying the heated products to an enlarged reaction chamber, 20 also maintained at substantial superatmospheric pressure, wherein appreciable further cracking thereof is accomplished, supplying both vaporous and liquid conversion products from the reaction chamber to a reduced pressure vaporizing and 25 separating chamber, wherein appreciable further vaporization of said liquid products is accomplished and wherein vaporous products are separated from the resultant residual liquid, fractionating the vaporous products from said vaporizing and separating chamber for the formation of reflux condensate, separating said reflux condensate into selected relatively low-boiling and 30 high-boiling fractions, returning said high-boiling fractions of the reflux condensate to the heating coil for further cracking, subjecting fractionated vapors of the desired end-boiling point to condensation, recovering the resulting distillate, 35 commingling at least a substantial portion of said residual liquid with regulated quantities of said selected low-boiling fractions of the reflux condensate, passing the resultant mixture through a separate heating coil and heating the same 40 therein at substantial superatmospheric pressure to a sufficiently high temperature to induce subsequent coking of its high-boiling components and appreciable cracking of its low-boiling components, regulating the conditions of treatment in said separate heating coil to maintain said mixture in a mixed-phase condition therein, dis- 45 charging the resultant highly heated mixture

from said separate heating coil and introducing the same into an enlarged coking zone, also maintained at a sufficiently high superatmospheric pressure to effect appreciable cracking of the vaporous components of the mixture at their 5 attained temperature in this zone and wherein the non-vaporous high-boiling components of the mixture are reduced to coke, removing resultant vaporous products, including any entrained high-coke forming materials, from the coking zone, 10 and supplying the same to said vaporizing and separating chamber.

12. A process such as defined in claim 11 wherein charging stock for the process, comprising a hydrocarbon oil of relatively wide boiling 15 range, is supplied to said fractionating step wherein relatively low-boiling and high-boiling components thereof commingle, respectively, with said selected low-boiling and high-boiling fractions of the reflux condensate. 20

13. A process such as defined in claim 11 wherein charging stock for the process, comprising essentially an oil of higher boiling characteristics than said selected low-boiling fractions of the reflux condensate, is supplied for 25 cracking to the first mentioned heating coil.

14. In a process of hydrocarbon oil conversion wherein the oil is heated in a heating zone, the heated oil discharged into an enlarged reaction zone, superatmospheric pressure maintained on 30 the heating zone and enlarged reaction zone, all of the products of reaction being withdrawn from the enlarged reaction zone and discharged into an enlarged reduced pressure zone wherein vapors separate from non-vaporous residue, the 35 vapors being fractionated to form primary and secondary reflux condensates and the primary reflux condensate resulting from such fractionation being returned to the heating zone admixed with fresh charging stock, the improvement 40 which comprises withdrawing regulated portions of the non-vaporous residue from the reduced pressure zone and combining the same with said secondary reflux condensate, subjecting the resultant mixture to heat, discharging said heated 45 mixture into an enlarged coking zone, the temperature conditions in the residue heating zone being controlled to reduce the residue in said coking zone to coke.

JOSEPH G. ALTHER. 50
